UNITED STATES PATENT OFFICE.

GEORGE F. BAKER, JR., OF CHICAGO, ILLINOIS, ASSIGNOR TO POPULAR MECHANICS CO., OF CHICAGO, ILLINOIS, A CORPORATION OF ILLINOIS.

ADVERTISING DEVICE.

Application filed May 21, 1928. Serial No. 279,505.

My invention relates to advertising devices and particularly to a novel structure intended as a display device for magazines.

A fundamental idea in connection with 5 the device is to provide a display that will show the cover page of a current issue of the magazine; second, that will indicate to a possible purchaser that a supply of the magazines is on hand and, third, that will 10 cite the curiosity of the public as to how a light can be caused to shine through a body of stacked magazines.

These objects are attained in a structure of very simple form, a description of which 15 will follow.

The invention will be more readily understood by reference to the accompanying drawings, in which—

Fig. 1 is a perspective view of the device 20 constructed in accordance with my invention;

Fig. 2 is a vertical sectional view thereof; and,

Fig. 3 is an enlarged sectional detail on 25 the line 3—3 of Fig. 2.

In the drawings, it will be seen that the device of my invention includes a base 10, which may be hollow and constructed of sheet metal if desired, the exterior face being 30 colored, lettered and lined to indicate a stack of the magazines that are offered for sale.

The upper portion 11 of the device likewise 35 consists of a hollow sheet metal body, the side walls of which are suitably printed and decorated to indicate a leaning or inclined stack of the same magazines resting on top of the stack represented by the base 10. An electric lamp 12 of the flasher type 40 is placed within the casing 11 and a cover 13 serves to close the top thereof.

The front wall of the casing is constructed 45 to provide two flanges 14, 14¹ extending from top to bottom along the side edges of the casing and adapted to receive two sheets 15, 16 of transparent material such as celluloid or glass. Between these sheets of transparent material the cover page 17 of the current issue of the magazine is inserted.

The paper on which the cover is printed being semi-transparent, the light from the lamp 12 will shine through the three layers of material constituting the front wall and accentuate the illustrations, colors and lettering of the cover. 50

When the issue of the magazine is obsolete and a new issue arrives, the dealer will remove the cover page of the past number and insert one of the current issue. The unique display will attract the attention of 60 possible customers and serve materially to increase the sales. The device is of very simple and economical construction and requires no attention other than the changing 65 of the cover pages from time to time.

While I prefer to utilize a flasher lamp, it will be apparent that advantageous results may be secured by the use of an ordinary continuously burning lamp. Modifications and variations in the form and arrangement may be made and I do not wish to be limited except as indicated in the appended 70 claims.

I claim:

1. In an advertising device, the combination of a base, a hollow casing constructed to simulate a plurality of vertically stacked magazines resting on said base, a wall of said casing being transparent, means in said transparent wall for receiving the cover of 80 a magazine that is advertised, and a source of light in said casing adapted to shine through said transparent wall and said cover. 75

2. In an advertising device, the combination of a base, a hollow casing constructed to simulate a plurality of vertically stacked magazines resting on said base, a wall of said casing being transparent, means in said transparent wall for receiving the cover of a 90 magazine that is advertised, and a source of light in said casing adapted to shine through said transparent wall and said cover, the remaining walls of the casing being opaque. 85

In testimony whereof I have affixed my 95 signature.

GEORGE F. BAKER, JR.
